(57) **CLAIM**

The ornamental design for a stacked hitch assembly, as shown and described.

DESCRIPTION

FIG. 1 is a front isometric view of the stacked hitch assembly;

FIG. 2 is a rear isometric view of the stacked hitch assembly of FIG. 1;

FIG. 3 is a front view of the stacked hitch assembly of FIG. 1;

FIG. 4 is a rear view of the stacked hitch assembly of FIG. 1;

FIG. 5 is a right side view of the stacked hitch assembly of FIG. 1;

FIG. 6 is a left side view of the stacked hitch assembly of FIG. 1;

FIG. 7 is a top view of the stacked hitch assembly of FIG. 1; and,

FIG. 8 is a bottom view of the stacked hitch assembly of FIG. 1.

The broken lines depict portions of the stacked hitch assembly that form no part of the claimed design, and are for illustrative purposes only.
